CLAIM

The ornamental design for a kitchen box top opener, as shown and described.

DESCRIPTION

FIG. 1 is a perspective view of a kitchen box top opener showing our new design, the flap-type box top and human hand in broken lines for illustrative purposes only;

FIG. 2 is a perspective view thereof, the spout-type box top and human hand in broken lines for illustrative purposes only;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view thereof; and

FIG. 8 is a rear elevational view thereof.
